INSIDE OF A BUILDING UNIT FOR USE AS THE UPPER PART OF A BATHROOM

David Charles Kirby, 28 Warren Way, Digsowell,
Welwyn, England

Filed Dec. 1, 1964, Ser. No. 82,850

Claims priority, application Great Britain June 1, 1964

Term of patent 14 years

(Cl. D4—4)

Fig. 1

*Fig. 3*FIGURE 1 is a top perspective view of a building unit for use as the upper part of a bathroom and showing my new design;

The dominant feature of my design resides in the portions shown in full lines.

I claim:

The ornamental design of a building unit for use as the upper part of a bathroom, substantially as shown and described.
